OTHER PUBLICATIONS

Design U.S. Appl. No. 29/558,188, filed Mar. 15, 2016.
Design U.S. Appl. No. 29/559,575, filed Mar. 30, 2016.Primary Examiner — Rosemary K Tarcza
Assistant Examiner — Nathaniel D. Buckner(57) **CLAIM**

We claim the ornamental design for a battery, as shown and described.

DESCRIPTION

FIG. 1 is a perspective view of a battery disclosed herein;
FIG. 2 is another perspective view thereof;
FIG. 3 is a top view thereof;
FIG. 4 is a bottom view thereof;
FIG. 5 is a rear view thereof;
FIG. 6 is a front view thereof;
FIG. 7 is a first side view thereof; and,
FIG. 8 is a second side view thereof.
Broken lines illustrate environmental structures that form no part of the claimed design.

1 Claim, 5 Drawing Sheets(56)
